UNITED STATES PATENT OFFICE.

JESSIE E. VIRDEN, OF PHILADELPHIA, PENNSYLVANIA.

WASHING APPARATUS.

1,226,283.

Specification of Letters Patent.

Patented May 15, 1917.

Application filed April 29, 1916. Serial No. 94,298.

To all whom it may concern:

Be it known that I, JESSIE E. VIRDEN, a citizen of the United States, residing at Philadelphia, county of Philadelphia, and 5 State of Pennsylvania, have invented a new and useful Improvement in Washing Apparatus, of which the following is a full, clear, and exact description, reference being had to the accompanying drawings, which form 10 a part of this specification.

My invention relates to that class of washing machines used in connection with wash tubs, but which are operated without direct submersion in the water.

15 More particularly, my invention is used in conjunction with a corrugated wash board which may be positioned upon the top of a wash tub, the clothes being lifted from the water onto the washboard and there scrubbed 20 by means of my improved washing device. My device is in the form of a hollow pad with a corrugated face for scrubbing purposes, and provided with a handle by which it may be operated. The washing 25 pad may be used independently upon an ordinary wash board or it may be mounted on rollers in connection therewith, provision being made for raising the pad, in the latter case, for the placing of the wash there- 30 under.

I will now describe in detail the construction and operation of one preferred embodiment of my invention, in connection with the accompanying drawings, in which—

35 Figure 1 is a plan view, and Fig. 2 a perspective view, of my washing device in connection with an ordinary wash tub. Fig. 3 is an enlarged detail shown partly in section. Fig. 4 is an enlarged cross section 40 through, and a portion of, a wash board.

The main element of my device is a hollow washing pad *a* having its under face *b* corrugated, as shown in Fig. 4, the corrugations being relatively closer than the corrugations of the wash board *c* with which it is used. Pad *a* has a latchable door *d*, by which soap *x* may be inserted. The corrugated face *b* is perforated to allow of the 45 passage of water to and from the soap.

50 In use the garment to be washed, after being thoroughly wetted, is placed upon the wash board *c*, and the pad *a* is then placed thereon with its corrugations running parallel with those of the wash board, and 55 rubbed vigorously thereover in a direction

at right angles to said corrugations. In other words, the washing pad takes the place of the hands in the ordinary process of hand washing, but with much better results, and much less labor.

60 The handle of the washing pad may be arranged on its top, or on one of its sides, as most convenient, and the washing pad may be used loosely and separately, or it may be connected up to slide in a runway 65 over the washboard as shown in the drawings.

The washing pad *a* is here shown with a handle *e* in front and at the back is hinged at *f* to a frame carrying wheels *g* in a groove 70 *j* in one of the longitudinal members *h* of the washboard.

75 Members *h* are of sufficient length to cover any ordinary tub, round or square, and are supplied with holes in which pins *i* may be inserted to confine said members against the tub sides and prevent any relative movement of the washboard, holding it securely during the washing operation.

80 The washing pad is raised on its hinge, by handle *e*, and wet clothes are lifted from the tub and placed upon the washboard. Then the pad is brought down upon them and moved vigorously over them, the wheels *g* running back and forth in groove *j*.

85 In order to take the reaction of the pressure brought to bear upon handle *e* in this operation, I provide rollers *k* upon the ends of the pins upon which wheels *g* turn. These rollers are arranged to bear against 90 the under side of a channel section *l* attached to rear member *h*.

95 Thus the parts *f*, *g*, *h* form a carriage, confined in its movement by slot *j* and channel *l*, and forming a guide for the washing pad. Pad and carriage may be readily removed by moving them endwise out from beneath the channel section *l*.

A wheel *m* mounted on handle *e* may be 100 provided to run in corresponding groove *n* in the front member *h*, if desired, to further enhance the ease of movement of the washing pad.

105 In order to hold the washing pad in its raised position while arranging the clothes to be washed upon the wash board, I have provided a stand *p* attached to the washing pad. When the latter is turned up upon its hinge *f*, instead of falling over backward, stand *p* is made so as to come to rest 110

upon channel 7 and support the washing pad in its raised position. Thus the operator's hands are both free to attend to arrangement of the clothes, etc.

5 The washboard is preferably of the corrugated form, and it has been found to produce better results if the corrugations are wider or farther apart than the corrugations in the washing pad, so that they will never fit into each other, but each separately engage the intervening clothes. This is true whether the washing pad is used with rollers, or is used in loose form and simply applied to the wash board by hand
10
15 as first described.

Having now fully described my invention, what I claim and desire to protect by Letters Patent is:

20 1. A washing apparatus comprising a washboard having a runway near one longitudinal edge thereof, an overhanging member extending along the same edge of the board, a carriage and means thereon engaging said runway and overhanging member, and a pad pivoted on the carriage on an axis extending parallel with said runway and adapted to be swung to and from the washboard.
25

Copies of this patent may be obtained for five cents each, by addressing the "Commissioner of Patents, Washington, D. C."

2. A washing apparatus comprising a washboard having runways adjacent to its opposite longitudinal edges, an overhanging member extending along one edge of the washboard, a carriage movable between one of the runways and said overhanging member, a pad pivoted on the carriage on an axis extending parallel to the last named runway and adapted to be swung toward and from the washboard, and means on the free end of the pad adapted to movably engage the other runway.
30
35
40

3. A washing apparatus comprising a washboard having a runway near one longitudinal edge thereof, a piece secured along the same edge of the board having an overhanging member, a carriage, two rollers movable with the carriage, one engaging the runway and the other extending under said overhanging member, a pad pivoted on the carriage, and a handle on the pad whereby the latter may be reciprocated along the 45
50 board.

In testimony of which invention, I have hereunto set my hand, at Philadelphia, on this 28th day of April, 1916.

JESSIE E. VIRDEN.
